UNITED STATES PATENT OFFICE.

HUBERT L. JUDD, OF BROOKLYN, NEW YORK.

DESIGN FOR A SHADE-PULL.

SPECIFICATION forming part of Design No. 14,847, dated March 4, 1884.

Application filed November 22, 1883. Term of patent 7 years.

To all whom it may concern:

Be it known that I, HUBERT L. JUDD, of Brooklyn, in the county of Kings and State of New York, have invented and produced a Design for a Shade-Pull, of which the following is a specification.

This design relates to the ornamental appearance of the shade-pull; and it consists in a clip, ornamental corrugated globes or balls, and a flat ring, as represented in the accompanying drawings, in which—

Figure 1 is an elevation of the said shade-pull, and Fig. 2 is a side view of the same.

The clip N has the sides 1 1 and segmental edges 2 2, as represented. From these are suspended the two corrugated balls or globes B and C and the ring D. Within this ring is suspended another corrugated globe or ball, E.

The appearance of this shade-pull is highly ornamental, the corrugated balls, the ring, and the clip having a pleasing, artistic appearance, and the ring is adapted to being grasped in raising and lowering the shade.

I claim as my invention—

1. The herein-described design for a shade-pull, consisting of a flat ring suspended beneath a corrugated ball, substantially as set forth.

2. The herein-described design for a shade-pull, consisting of a flat ring suspended below a corrugated ball, and having a corrugated ball hung within the ring, substantially as shown.

3. The herein-described design for a shade-pull, consisting of a flat ring suspended below a corrugated ball, and having a corrugated ball within the ring, and a clip with segmental edges above the upper ball, substantially as shown.

Signed by me this 12th day of November, A. D. 1883.

H. L. JUDD.
